UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

FOCUSING DEVICE.

Application filed May 6, 1926. Serial No. 107,095.

My invention relates to means for supporting a lamp-socket and for moving the socket longitudinally of the supporting means to shift the position of the filament of a lamp-bulb mounted in the socket, and more particularly to the class of lamp focusing devices in which a socket is movable by means of a screw which is operatively interposed between the socket shell and a thrust member connected to a holder for the socket.

In automobile headlights employing this class of focusing arrangements, it has heretofore been customary to fasten the thrust member to a tubular holder carried by the reflector of the lamp and to have the head of the focus-adjusting screw project through a perforation in the back of the lamp casing. In practice, this guiding perforation in the casing (which should slidably fit the screw head to exclude rain and dust from the casing) is rarely in alignment with the holder by which the socket shell is slidably carried, thereby causing a cramping of this shell in the holder and interfering with the adjusting if the shell closely fits the holder. On the other hand, if the holder fits the shell so loosely as to avoid this cramping, the socket shell not only may rattle in the holder but also is apt to be tilted so as to move the lamp filament off the axis of the reflector on which the holder is mounted.

My present invention aims to overcome all of these difficulties by providing a universal joint between the socket shell and the adjusting screw, and by arranging thrust means so that they will rigidly space the head of the screw from the holder longitudinally of the latter while permitting relative movements of these parts in other directions to compensate for any lack of alignment between the holder and the guide for the screw head. It also provides for an assembly of the parts in which a single spring holds the thrust member on the holder and permits the said movement of the thrust member with respect to the holder.

Still further and also more detailed objects will appear from the following specification and from the accompanying drawings, in which

Fig. 1 is a vertical section through a portion of an automobile headlamp equipped with an embodiment of my invention, with

the reflector and the back of the lamp case shown in section.

Fig. 2 is a bottom view of the same parts, with the reflector and the lamp casing omitted.

Fig. 3 is a section taken along the line 3—3 of Fig. 1.

Fig. 4 is a plan view of the sheet metal blank from which the doubly forked member of my focusing device is formed.

Fig. 5 shows the sheet metal blank from which the companion singly forked member is formed.

In the drawings, the reflector 1 has its usual axial perforation substantially in alignment with the bore of an eyelet 2 which is clinched through a perforation in the back 3 of the lamp. Extending rearward of the reflector and coaxial with the reflector is a tubular holder 4 which is clinched at its forward end to the reflector. Slidably fitting the bore of this holder is the shell 5 of a lamp-socket, which shell has bayonet slots 6 at its forward end for interlocking with the usual anchoring pins on a lamp-bulb 7. The bottom 5^A of this socket shell has a rearwardly directed tubular extension 8 extending through a bore 9 in the bight 10 of a U-shaped member which has its arms 11 directed rearwardly, and the free end of the extension 8 is flared outwardly as shown in Fig. 1 to clamp this tubular member rigidly to the bottom of the socket shell.

Fitting snugly between the said arms 11 are the two forwardly directed arms 12 of a doubly forked member which has its rearwardly directed arms 13 perforated to serve as journals for a shaft 14 into which the adjusting screw 15 is threaded transversely of that shaft, so that this shaft serves as a nut. The screw 15 has its head provided with a peripheral groove 15^A spacing a forward collar 15^B from the rear end 15^C of the screw head, and this rear end (which has the usual transverse slot to receive a screw-driver) extends slidably into or through the bore of the eyelet 2.

Interposed between the holder 4 and the screw is a thrust member which has one arm 16 extending longitudinally of the holder and which has a nub 17 fitting into a lateral perforation in the holder to connect the thrust member pivotally to the holder. The thrust member also includes a rear arm 18

extending across the axis of the holder and having the adjusting screw 15 swiveled in it as hereafter described, and this screw preferably has an enlarged forward end 15^b disposed forwardly of the arm 18 to limit the possible rearward movement of the screw with respect to that arm.

To hold the thrust member in its said pivoting relation, I provide a contractile bowed spring 19 which partially encircles the holder, and which has its lower portion engaging the bottom of the holder while its upper part presses downwardly against the arm 16 of the thrust member. This spring and the holder desirably have interfitting formations, such as a longitudinal ridge 20 on the holder and a corresponding hump 19^b on the spring to prevent the spring from rotating on the holder along with the thrust member, and I desirably provide the socket shell 5 with a projection 22 entering the groove formed by the hump 20 so as to prevent this shell from rotating in the holder.

The upper part of the spring 19 has a downwardly directed nub 21 entering a recess in the arm 16 to cooperate with the nub 17 in pivoting the thrust member to the holder. This nub 17 preferably is of such a length as to project through the pivoting perforation in the holder and into engagement with the socket shell 5, so that the spring acts through this nub to clamp the socket shell against the bottom of the bore of the holder, thereby taking up any lost motion which might be due to a loose fit of this shell in the holder.

The rear arm 18 of the thrust member is desirably forked to provide two fork arms extending through the groove 15^a so as to be disposed between the longitudinally spaced parts 15^b and 15^c of the screw head, thereby affording the swiveling connection between the arm 18 and the adjusting screw, and these forks desirably are curved about an axis corresponding to the axis of the nut 14 when this nut is in its medial position of adjustment.

With the parts thus arranged, and with the forward arms 12 of the double forked member pivoted to the arms 11 of the U-shaped member by any suitable means—as by a cotter pin 21—this pivoting cooperates with the journaling of the nut 14 to afford a universal joint between the screw and the socket shell to which the arms 11 are rigidly connected. Consequently, the screw can rock about the axis of the said journaling to compensate for variations in the alinement of the holder and the eyelet 2 in one direction, such movement being permitted by the curving of the forks of the arm 18; while the pivoting of the thrust member to the holder allows the thrust member to swing in another direction to compensate for any lateral displacement of the eyelet axis

with respect to that of the holder. In other words, the screw head is rigidly spaced from the holder longitudinally of the latter but is free to move in all other directions with respect to the holder.

However, while I have illustrated and described an embodiment in which the arms 11 (which effectively are a part of the socket shell) form parts of an initially separate U-shaped member, I do not wish to be limited to this or other details of the construction and arrangement thus disclosed, it being obvious that many changes might be made without departing either from the spirit of my invention or from the appended claims.

I claim as my invention:

1. In a lamp, a reflector, a tubular socket holder mounted on and opening through the reflector, a lamp body having a perforation approximately in axial alinement with the said holder, a lamp socket having its shell slidably mounted in the said holder; and a focusing device carried by the said holder for sliding the socket in the latter; the focusing device comprising a screw having its head projecting into the said perforation, a nut threaded on the screw, a universal joint interposed between the nut and the socket shell, and a thrust member carried by the holder, the screw having a swiveling connection to the thrust member.

2. A lamp construction as per claim 1, in which the thrust member is pivoted upon the holder.

3. A lamp construction as per claim 1, in which the thrust member is pivoted upon the holder and in which the swiveling connection of the thrust member to the screw permits movement of the screw in a plane extending through the axis of the pivotal connection between the thrust member and the holder.

4. A lamp construction as per claim 1, in which the holder has a lateral perforation and the thrust member has a projection journaled in the last named perforation and engaging the socket shell; in combination with spring means for pressing the said projection against the socket shell.

5. A lamp construction as per claim 1, in which the holder has a lateral perforation and the thrust member has a projection journaled in the last named perforation; in combination with an arcuate spring extending partly around the holder and having a portion engaging the exterior of the holder, the spring having another portion engaging the outer face of the thrust member, the thrust member and the spring having interengaging formations in alinement with the last named perforation.

6. A lamp construction as per claim 1, in which the screw has a peripheral groove, and in which the thrust member has a forked portion extending transversely of the screw

and disposed with the shanks of the forks extending through the groove at opposite sides of the axis of the screw.

7. A lamp construction as per claim 1, in which the screw has a peripheral groove, and in which the thrust member has a forked portion disposed with the shanks of the forks extending through the groove at opposite sides of the axis of the screw, the said forked portion being curved about an axis corresponding substantially to the axis of the nut when the nut is in its medial position.

8. A lamp construction as per claim 1, in which the universal joint comprises a pair of arms fast upon, and extending rearwardly from the socket shell; and a member pivoted to the nut and to the said arms on relatively transverse axes.

9. A lamp construction as per claim 1, in which the universal joint comprises a pair of arms fast upon, and extending rearwardly from the socket shell, and a member having a pair of arms in which the nut is journaled; the last named member also having a second

pair of arms pivoted to the arms on the socket shell on an axis at right angles to the axis of the nut.

10. In a lamp, a reflector, a tubular socket-holder mounted on and opening through the reflector, a lamp body having a perforation approximately in axial alinement with the said holder, a lamp socket having its shell slidably mounted in the said holder; and a focusing device carried by the said holder for sliding the socket in the latter; the focusing device comprising a screw having its head projecting into the said perforation, a nut threaded on the screw, a universal joint interposed between the nut and the socket shell, and thrust means interposed between the head of the screw and the holder for rigidly spacing the screw head from the holder longitudinally of the latter while permitting movement of the screw head with respect to the holder in all other directions.

Signed at Detroit, Michigan, April 28th, 1926.

CHARLES E. GODLEY.
